UNITED STATES PATENT OFFICE.

FRANK F. STANEK, OF HOWELL, NEBRASKA.

HORSESHOE.

976,408.

Specification of Letters Patent. Patented Nov. 22, 1910.

Application filed March 29, 1910. Serial No. 552,173.

To all whom it may concern:

Be it known that I, FRANK F. STANEK, a citizen of the United States, residing at Howell, in the county of Colfax and State 5 of Nebraska, have invented a new and useful Improvement in Horseshoes, of which the following is a specification.

This invention relates to certain new and useful improvements in horseshoes, and 10 more particularly to that class of horseshoes having removable calks, the object being to provide a horseshoe which is exceedingly strong in construction and one in which the calks are so mounted that they can be readily 15 attached or detached, and when in position are held firmly in place without the use of fastening members of any kind.

Another object of my invention is to provide a horseshoe which is strengthened at 20 the toe and heel portions by enlarging the same.

A still further object of my invention is to provide a shoe which is formed of such a shape that the same will conform to the 25 shape of the foot of the animal to which it is secured, and one which is provided with the usual openings to receive the nails for securing the same.

A still further object of the invention is to 30 provide the enlarged portions of the shoe with tapering dove-tail shaped grooves in which are adapted to fit the dove-tail shaped heads of calks which are placed therein from the inside of the shoe and locked in position 35 by being forced outwardly in such a manner that they will be held in their adjusted positions without any danger of the calks becoming detached when in use, as the tendency of the calks of a horseshoe are to work 40 outwardly, whereby the calks will become more firmly secured after they have been used.

With these objects in view, the invention 45 consists in the novel features of construction, combination and arrangement of parts, hereinafter fully described and pointed out in the claims.

In the drawing forming a part of this specification: Figure 1 is a perspective view 50 of my improved horseshoe. Fig. 2 is a trans-

verse section. Fig. 3 is a horizontal section through the toe portion of the shoe.

In carrying out my improved invention I employ a horseshoe proper A, preferably formed of steel which is provided with an 55 enlarged toe-portion B and heel portions C, the enlarged toe portion being provided with a nail receiving opening B', and the horseshoe proper with nail receiving openings A', for securing the same to the hoof 60 of an animal in the ordinary manner. The enlarged portion B is provided with a central notch B² which communicates with tapering dove-tailed shaped grooves B³, extending transversely through the enlarged portion, and in which are adapted to be placed 65 dove-tailed shaped heads D' of calks D which are substantially square in cross section and are provided with pointed ends, as clearly shown. While I have shown and described 70 these calks square, it is of course understood that they could be formed round and provided with dove-tailed shaped heads. In placing the calks in position within the grooves, they are inserted through the notch 75 and forced outwardly by a punch until they are wedged by the tapering grooves, in such a manner that they will be held without any danger of them slipping. Dove-tailed shaped grooves C' are also formed in the 80 enlarged heel portions C extending substantially longitudinally with the side bars of the shoe, and are formed tapering in a similar manner to the grooves of the toe portions, and in which are adapted to be driven from 85 the inside calks D, and it will be seen that the grooves are of the same size whereby calks of the same size and shape are used for the heel calks as well as the toe calks.

Having thus fully described my invention, what I claim as new and desire to secure by Letters Patent is:—

1. A horseshoe provided with an enlarged toe portion having a central notch in its inner edge, said notch communicating with tapering dove-tailed shaped grooves, and calks having dove-tailed shaped heads adapted to be inserted in said grooves through said notch and forced outwardly.

2. A horseshoe having an enlarged toe

portion and enlarged heel portions, said enlarged portions being provided with tapering dove-tailed shaped grooves, the enlarged portion of the toe being provided with a central notch communicating with the grooves, and toe and heel calks having dove-tailed shaped heads adapted to be

placed in said grooves and forced outwardly for locking said calks in said grooves by frictional contact.

FRANK F. STANEK.
